UNITED STATES PATENT OFFICE.

BENJAMIN A. LEGG, OF COLUMBUS, OHIO, ASSIGNOR TO JOSEPH A. JEFFREY, OF SAME PLACE.

ROCK-DRILL.

SPECIFICATION forming part of Letters Patent No. 317,949, dated May 12, 1885.

Application filed December 4, 1884. (No model.)

To all whom it may concern:

Be it known that I, BENJAMIN A. LEGG, a citizen of the United States, residing at Columbus, in the county of Franklin and State of Ohio, have invented certain new and useful Improvements in Rock-Drills, of which the following is a specification, reference being had therein to the accompanying drawings.

Figure 1 is a front elevation of the operative parts of the drill, the screw-rod being shown in section. Fig. 2 is a rear view of the same. Fig. 3 is a central vertical section. Fig. 4 is a top plan view, the supporting-frame being shown in section. Fig. 5 shows the relation of the screw-shaft to the nut-sections. Fig. 6 illustrates the connection between the braces or legs of the frame and the screw-rods which engage therewith. Fig. 7 is a side view of the machine complete, except as to the drill 20 or bit, which is partly broken away.

In the drawings I have shown the drill and the devices for operating it as being mounted in an improved frame or support which I have devised. This consists of the main frame 25 and a supplemental bracing-frame. The main frame has the parallel bars A A, preferably rounded at the top and bottom to form connections, as at A'.

B B' are screw-rods, one at the top and one 30 at the bottom, rigidly secured to the main frame, they being adapted to receive the braces C C', which latter are shod with points or projections, by means of which they can be fastened directly to the roof and floor of a mine, 35 or to other upper and lower holding-surfaces.

C² C² are hand-wheels by which the parts C C' can be rotated, the latter having external threads, which engage with the rods B B'.

To this main frame there is secured a supplemental frame consisting of two side bars, 40 E E, preferably curved about as shown, and having their upper and lower ends bolted to the side bars of the main frame.

E' is a yoke or stirrup, the bars of which 45 are hinged at e to the supplemental frame, this yoke carrying the screw-rod E², which engages with a rear brace, E³. This brace receives the back-thrust from the drill, and has an external thread, which engages with the 50 same rod E², and a hand-wheel, e'.

In the main frame A A is hinged or mounted

the support for the drill and its feed-screw, and the bed-frame which carries the parts by which power is imparted to the drill.

F represents a plate, from the lower side of 55 which there projects a tubular support, F'. f f are projections provided with sockets at f', into which are fitted with requisite tightness the pivots or screws f² f², these engaging with threaded sockets f³ f³ in the main frame. 60 Upon these the drill and the operative parts can be rocked so as to throw the point of the drill up or down, as required. The drill may be, in construction, of any well-known or of 65 any preferred style.

The heel is seated in a socket formed in the end of the feed-screw G'. The part which directly supports the feed-screw, and at the same time imparts rotation thereto, is the hub H' of the wheel H and a sleeve, H², which 70 projects inward from the hub, and is mounted in the tubular support F'. This hub or sleeve (or both of them) fits closely to the screw and has a spline or feather, which takes into a longitudinal groove formed in the feed-screw G', 75 so that when the wheel and sleeve turn they shall rotate the screw, and at the same time permit it to be moved longitudinally to force the drill into the rock.

The tubular support F' is provided at one 80 end with an outwardly-projecting rim or flange, F², its outside diameter being substantially the same as the outside diameter of the hub H'.

h h are clips screwed fast to the hub and 85 overlying the flange F², and extending over the corner of the flange, as plainly shown in Fig. 3, so as to confine the parts in proper working relation. Of course any desired number of these clips may be employed.

The feed-screw is caused to move longitudinally by means of a nut formed in two parts, 90 I I, said parts being supported upon the plate F and moving relative thereto. As shown, the said parts of the nut consist each of a semi-cylinder. Each of these is formed with or secured to a plate, i i, which plates are secured to the plate F by a dovetail joint, so that they can be moved relatively thereto. Each plate i has a pin, i', projecting upward through a slot, i², in the plate F, and with these pins there engages a lever, J, having a cam-plate,

j, at the end. In this plate there are slots *j'j'*, into which enter the pins *i'.* The lever-plate is mounted upon a stud, *F'*, carried by the plate *F*, and the slots *j'j'* are struck from centers eccentric to the stud or pin *F'.*

It will be seen that when the lever *J* is moved in one direction the pins *i'* will be drawn inward toward the plane of the screw-shaft, and when the lever is moved in the opposite direction they will be thrown outward. With them will move the nut-pieces *I I* into or out of engagement with the shaft *G'.*

The wheel *H*, which, as above said, rotates the feed-screw, and with it the drill, is in turn rotated by the main power-pinion *K*. This is mounted upon a shaft, *K'*, which passes through the center of the engine-cylinder *L*. This cylinder is mounted upon and rigidly secured to the above-described plate *F*, the lateral wall *l* of the cylinder being preferably cast with a supplemental plate, *L'*, which projects sufficiently far to receive the bolts at *l'*. As shown, the cylinder is cast with said side wall, *l*, and one end or face wall, *l'*, integral. The other end or face wall, *l'*, is formed separately from the cylinder and subsequently bolted thereto. At *l'* there is a hollow cylindrical offset, in which the end of the shaft *K'* is mounted. The wall-plate *l'* is formed with a journal-cylinder, *l'*, on the exterior of the end which is a screw-thread, which engages with the threaded cap *l'*, and through this cap passes the said shaft *K'*.

The shaft *K'* carries the piston *M*, which consists of a cylinder, preferably of substantially the dimensions shown. The shaft *K* passes through it eccentrically, it being so arranged relatively to the shaft and to the interior face of the cylinder that it always pre-40 serves a tight joint with said interior surface.

Above the cylinder is the chest *N*, which initially receives the steam, compressed air, or other motive agent, this chest having a coupling-piece at *N'*, to which a pipe or rubber hose, *O*, may be secured.

P represents the abutment or cut-off, the lower edge of which is permanently in contact with the surface of the piston, and which is constructed with the feed-port *p*, for the steam or air. One end of said port is permanently in communication with the interior of the steam-chest, and the other end delivers the steam to the rear side of the piston.

At *Q* the exhaust-port is situated, the inner end of it being as near as practicable to the abutment *P*. At the outer end of this exhaust-port there is a coupling, to which, if desired, may be attached a pipe or hose.

The method of operating the machine will be readily understood: The main frame is first set and properly braced above and below, and the supplemental brace at the rear is made rigid in the required position. The parts of the nut *I I* are withdrawn from the shaft, and the latter is drawn back, if necessary, and after this the nut-pieces *I I* are again brought into engagement with the screw. If steam or

air be admitted to the chest *N*, the piston will be caused to revolve continuously, it imparting at each of its rotations one to the pinion *K*. The latter engages with the internal teeth of the wheel *H*, which in turn revolves the feed-screw. As the screw revolves it is caused to advance by reason of the engagement of the nut with its thread.

I am aware of the fact that prior to my invention use has been made, in constructing mining-machines, of some of the elements separately considered—such as a screw-shaft, pivoting devices for joining the shaft to the main frame, &c.; but I believe myself to be the first to have devised a machine manifesting the constructions and combinations appearing in the claims below.

The screw is shown in the drawings, and is above described as resting entirely upon the hub or sleeve *H'* of the gear-wheel *H*; but said hub or sleeve need not be as long as represented, and the screw could have a supplemental tubular bearing or support which would be non-rotary. The screw is supported, it will be seen, independently of the nut.

Use has been heretofore made of nut-sections adapted to be attached to and detached from a screw-shaft, these being shown, for instance, in Patent No. 250,370, to F. M. Lechner, and I do not claim, broadly, such devices as are therein shown; but in my construction the nut-sections are arranged to slide rectilineally toward and from the shaft, they being supported independently of the levers which operate them. In mechanisms of the character shown in said patent the nuts are arranged to swing in circular paths, and they are more or less supported upon the adjusting devices. By having them arranged as mine are, they can be held positively and independently of the adjusting-lever.

Some of the advantages which I attain with the two nut-sections might be reached with a single nut, especially if it be arranged to slide rectilineally. I prefer the tongue-and-groove joint, though other means of uniting the nut and the bed-plate will readily suggest themselves which are the equivalents thereof. By having the elongated handle *J* the cam-plate *j* can be operated very readily.

As the engine is situated centrally relatively to the screw, the power can be applied advantageously and the weight of the various parts uniformly distributed.

The offset frame *E* enables me to apply the rear *Y*-shaped bracing-frame to great advantage, and I can bring the arms of the latter together and employ a single foot-brace without interfering with the operative parts.

What I claim is—

1. The combination, with the drill, the screw-shaft, and the tubular bearing through which the said shaft passes, of the expanded bed-plate or support secured to said bearing and pivotally connected to the frame, a rotary engine mounted upon the said bed-plate or support, the gear-wheel mounted upon the

axis of the screw, and the power-shaft connected directly with the piston, and also directly with said gear-wheel, substantially as set forth.

5 2. The combination, with the drill, the screw-shaft, and the tubular bearing through which said screw passes, of the main frame, the expanded bed-plate or support connected with said tubular bearing and pivotally joined 10 to the frame, the engine mounted upon said bed-plate or support centrally relatively to the screw, the gear-wheel mounted on the axis of the screw, the mechanism which connects the engine with the gear-wheel, and means 15 for detachably connecting the screw with the main frame, substantially as set forth.

3. The combination, with the drill, the screw-shaft which carries the drill, the tubular bearing or holder through which said screw 20 passes, and the main frame, of the expanded bed-plate or support secured to said tubular bearing or holder, the engine mounted upon said bed-plate or support, the gear-wheel mounted upon the axis of the screw, and the 25 pointed screws on the frame providing adjustable pivotal supports for the said bed-plate and tubular shaft-holder, substantially as set forth.

4. The combination, with the rotating drill, 30 and the screw-shaft which carries the drill, of the support for said shaft, and a detachable nut secured to said support by a tongue-and-groove joint, substantially as described.

5. The combination, with the rotating drill, 35 the screw-shaft which carries the drill, the support for said screw-shaft, and the lever having an elongated handle, of a nut supported on the frame independently of the le-

ver, and arranged to slide rectilineally toward and from the shaft, substantially as set forth. 40

6. The combination, with the rotating drill, the screw-shaft which carries the drill, a support for said screw-shaft, the cam-plate supported upon the frame, and an elongated lever connected therewith, of the nut formed in 45 two rectilineally-moving sections supported from the frame independently of the cam-plate and lever, and loosely connected with the latter, substantially as set forth.

7. The combination, with the rotary drill, 50 the screw-shaft which carries the drill, and the cam-plate, of the removable nut-sections supported independently of the said cam-plate, and a tubular support which holds the screw independently of said nut-sections, substan- 55 tially as described.

8. The combination, with the drill, the screw-shaft, and the tubular bearing for the screw, having a flange, F², at one end, of the gear-wheel having its hub mounted within the 60 said tubular bearing, and the clip or clips which engage with the said flange, substantially as set forth.

9. The combination, with the main frame having the adjustable braces for securing it 65 to the top and bottom of the mine, of the offset frame E and the rear bracing-frame having the upper Y-shaped part pivoted to the main frame, and having an extensible brace at the bottom, substantially as set forth. 70

In testimony whereof I affix my signature in presence of two witnesses.
